UNITED STATES PATENT OFFICE

WILLIAM BAIRD MARBLE, OF LOS ANGELES, CALIFORNIA, ASSIGNOR TO LATCHFORD
GLASS COMPANY, OF LOS ANGELES, CALIFORNIA, A CORPORATION OF CALIFORNIA

DESIGN FOR A BOTTLE

Application filed October 7, 1932. Serial No. 45,258. Term of patent 14 years.

To all whom it may concern:

Be it known that I, WILLIAM BAIRD MARBLE, a citizen of the United States, residing at Los Angeles, in the county of Los Angeles and State of California, have invented a new, original, and ornamental Design for Bottles, of which the following is a specification, reference being had therein to the accompanying drawing.

Referring to the drawing Fig. 1 is a side view of a bottle showing my new design which is the same on all four sides of the square bottle. Fig. 2 is a top view of my newly designed ornamental bottle.

I claim:

The ornamental design for a bottle, as shown and described.

In testimony whereof I affix my signature.

WILLIAM BAIRD MARBLE.
